[57] CLAIM

The ornamental design for a seat, as shown and de-
scribed.

DESCRIPTION

FIG. 1 is a front perspective view of a seat showing my
design in the form of a chair;

FIG. 2 is a side perspective view; and

FIG. 3 is a front perspective view of a seat showing my
design in the form of a loveseat.

The undisclosed bottom and rear surfaces of the seat
forms are all conventional in appearance.

FIG. 1

FIG. 2

U.S. Patent

Dec. 29, 1987

Sheet 2 of 2

D293,395

FIG. 3
